APPARATUS FOR APPLYING LIQUIDS TO
CONCRETE SURFACES

Albert D. Saunders, Great Neck, N. Y.

Application September 20, 1932, Serial No. 633,964

6 Claims. (Cl. 299—29)

This invention relates to an improved method of and apparatus for applying liquids to concrete surfaces and the like, and is particularly applicable to the coating of freshly laid concrete surfaces such as roadways or floor surfaces with a curing compound. The method and apparatus may, however, be utilized for applying waterproofing compounds for other purposes, coloring materials, road oils, etc.

In the setting of hydraulic cement such as the Portland cement utilized in the making of concrete roadways, floors and the like, it is well known that the proper setting of the concrete is due to hydration of the cement or chemical action between the cement and the water with which it is mixed. This hydration will not take place properly if the concrete dries out to any extent before the hydration is complete, and it is therefore important that the concrete shall be kept wet long enough to permit the required chemical action to be completed. The keeping of the concrete wet has commonly been done by various expedients such as covering it with earth or straw and sprinkling it at frequent intervals. Such expedients, however, are subject to numerous disadvantages, and in the United States patent to Hayden No. 1,684,671, an improved method of preventing evaporation of the water from the concrete during curing is set forth which comprises the application to the freshly laid concrete of an impervious coating which will retain all of the original mixing water in the concrete until the chemical reaction between the water and the cement has been completed, or, as it is commonly termed, until the concrete is fully cured. Suitable compounds for this purpose are set forth in said United States Letters Patent and also in United States Letters Patent to McRay No. 1,684,593.

In order to secure the full benefit of the processes and compounds set forth in said patents it is important that the curing compounds used be applied uniformly over the entire surface of the concrete, and be applied quickly and at the proper period after the laying of the concrete when conditions for application of the compounds are most favorable. When a volatile compound is employed, such for instance as one comprising an asphaltic base dissolved in a volatile oil, it is also highly desirable to secure rapid application so as to avoid difficulties due to evaporation of the solvent. Heretofore the compounds have been applied by means of a brush, mop, swab or single nozzle spray gun moved about above the surface of the concrete by ma-

nipulation in the hands of an operator. These methods are subject to numerous objections, particularly when employed on surfaces of large areas when numerous operators are required, which increases the cost of application and which prevents the obtaining of uniform results. When a brush, mop or swab is used there is danger of injury to the fresh concrete surface. With any of these hand manipulated methods of application, including the single nozzle spray gun carried by an operator, it is impossible to secure a coating of uniform thickness and parts of the concrete are almost sure to be insufficiently coated. In other places too much material is applied with consequent waste. Furthermore, if the coating is mixed with pigment, or is of such a nature as to color the concrete, a uniform appearance of the finished job cannot be obtained, but the surface will look patchy. This lack of uniformity will occur even where the coating is done by a single operator, and where several operators are working on different parts of a large surface the results will usually be even more unsatisfactory. Furthermore the coating material cannot be distributed simultaneously over a large area of the concrete, and therefore the condition of the latter may change during application of the coating and the best results will not be secured in the condition of the concrete itself.

In accordance with the present invention the objections above noted are overcome and a method and means are provided by which a large area of the concrete surface may be treated with the curing agent by one continuous operation in a uniform manner, and the same amount of coating can be applied on all parts of the surface. The human factor is practically eliminated and uniform satisfactory results may be relied upon. For instance in the use of my method and apparatus it is possible to treat the freshly laid concrete across an entire lane of a concrete highway and including where desired the vertical sides of the concrete strip in one continuous operation.

In the accompanying drawings in which certain preferred embodiments of the apparatus used in practicing the present invention are shown by way of illustration:

Figure 1 is a plan view of an apparatus suitable for applying a coating to a concrete roadway, a portion of one of the lanes of freshly laid concrete being shown in broken outline.

Figure 2 is a side elevation of the distributor shown in Figure 1, a part of the shield being broken away.

Figure 3 is a view, partly in side elevation and partly in vertical section showing the pressure distributing tank.

Figure 4 is a horizontal section of the pressure distributing tank on line 4—4 of Figure 3.

Figure 5 is a view partly in side elevation and partly in vertical section showing an improved form of spray nozzle which may be employed.

Figure 6 is a bottom plan view of the spray nozzle shown in Figure 5.

Figure 7 is a diagrammatic view showing a concrete roadway in cross section, and illustrating an arrangement of the spray nozzles for treating the vertical sides of the concrete lane, and also showing the adjacent spray nozzles for spraying the horizontal surface of the concrete.

Figure 8 is an end view of the form of distributing machine carriage shown in Figures 1 and 2 which is adapted to travel on the surface of the concrete.

Figure 9 is a similar view of a form of carriage for the distributing machine adapted to travel on the forms along the sides of the lane between which the concrete is laid; and

Figure 10 is a plan view of the carriage shown in Figure 9.

The apparatus chosen in the present instance to illustrate the invention and mode of carrying out the improved process, is of a type particularly adapted for the application of a curing agent to an elongated section of concrete, such as a lane of a concrete highway. In Figure 1 the outline of the concrete is indicated by the broken line 20. For applying the compound to the surface of this concrete a portable distributor 21 is provided which carries a plurality of spaced spray nozzles 22. The distributor has a frame comprising semi-circular members 25 connected by transverse members 26 and 27 which are attached to the ends of longitudinal beams 28, the latter being adapted to be supported on a suitable form of wheeled carriage to be described. Mounted on the frame is a pressure distributing tank 30 from which pipes lead to the various nozzles. As illustrated, a type of nozzle is utilized from which the liquid compound is adapted to be sprayed by means of compressed air and two pipes lead to each nozzle, one for supplying the liquid under pressure and the other for supplying the compressed air for atomizing purposes. In the drawings, the pipes for supplying the liquid to the nozzles are designated 31 and the pipes for distributing compressed air are designated 32. Each pair of these pipes leads to the respective branches of a Y 33, which carries a nozzle 22. The pressure distributing tank 30 is shown particularly in Figures 3 and 4 and is provided with a transverse partition 35 above which is a space for the liquid which is forced into it under pressure through an inlet opening 36, while below the partition 35 is a chamber for compressed air which enters through a port 37. The liquid discharge pipes 31 are connected to outlet ports 38 in the wall of the tank above the partition, while the air pipes 32 are connected to ports 39 in the wall of the tank below the partition. Preferably screens 41 and 42 are mounted transversely in the liquid and air chambers in the tank so as to prevent any foreign substance which may be forced into the tank from reaching the pipes leading to the nozzles and possibly clogging the pipes and nozzles so as to prevent uniform distribution of the liquid and air pressure to all the nozzles. Preferably the partition 35 slopes to a point immediately below the port 36 as shown in Figure 3, so as to facilitate the draining of the

liquid out of the pressure distributing tank when the apparatus is not in use.

The liquid compound and air under pressure are supplied to the pressure distributing tank in any suitable manner, for instance as illustrated diagrammatically in Figure 1. As here shown, a portable air compressor 50 is provided which is connected by means of an air hose 51 to an air pipe 52 which leads to the air inlet port 31 in the pressure distributing tank. An air cock 53 is preferably provided near the outer end of the pipe 52. A pressure material tank or reservoir 55 is provided for holding a supply of the coating liquid. Air pressure is supplied to the top of this tank above the level of the liquid therein, through a pipe 56 and the liquid is forced out of the bottom of the tank 55 under pressure through a liquid hose 57 which is connected to a liquid supply pipe 58 on the distributor, the end of such liquid supply pipe being connected to the liquid inlet port 36 in the pressure distributing chamber. A liquid cock 59 is preferably provided near the outer end of the pipe 58. A by-pass 60 controlled by a by-pass cock 61 is also preferably provided by means of which air may be forced into the pipe 58 for cleaning the liquid out of the distributing apparatus after the apparatus has been in use. In the normal operation of the apparatus, the by-pass cock 61 is closed and the air cock 53 and liquid cock 59 are opened wholly or partly. With this arrangement it will be seen that the liquid in the tank 55 is forced by the air pressure through hose 57 and pipe 58 into the upper chamber of the distributing tank 30 from which it is distributed through the pipes 31 to the several nozzles. At the same time air under pressure passes through the air hose 51 and pipe 52 to the lower chamber in the distributing tank and through pipes 32 to the nozzles. The proper mixture of air and liquid may be secured by adjusting the cocks 53 and 59.

By mounting the nozzles in the arc of a circle, the center of which is the pressure distributing tank 30, and by connecting the nozzles thereto by means of the radial pipes 31 and 32, it will be seen that all of these pipes are of the same length and therefore, by making the pipes and ports of equal diameter, the frictional resistance of the liquid and air passing to each nozzle will be the same. It is thus possible to secure uniform distribution of the liquid and compressed air to each nozzle. The supplying of the nozzles by means of pipes radiating from a central distributing tank of small diameter is also important in securing substantially uniform distribution of the liquid across the road surface irrespective of changes in the inclination of the surface due to the banking of the roadway. As the nozzles are supplied from the small tank located approximately centrally of the roadway, the flow of liquid will not be materially affected by the tipping of the apparatus and each nozzle will therefore receive the liquid at all times. This is not true where the liquid is supplied to the nozzles from a transverse header, because in that case the liquid will tend to flow to the part of the header which is lowest when the machine is tipped, and therefore the nozzles at the low side of the machine will be oversupplied, while the nozzles at the high side of the machine will be insufficiently supplied or not supplied at all.

The nozzles and radial pipes are preferably not uniformly spaced around the arc-shaped frame, but the nozzles nearer the center of the roadway are spaced more closely together than the nozzles near the outside, as shown in Figure 7.

1. The spacing should be such that the distances between the paths traversed by the nozzles when the distributor is moved longitudinally of the roadway or other concrete surface to be 5 treated are equal or substantially equal so that each nozzle will distribute its jet over an equal width of the concrete and a uniform distribution of the coating compound over the entire width of the roadway will be secured. The jets from 10 adjacent nozzles may barely contact or they may overlap. In either event if the nozzles are identical and properly spaced, a uniform distribution may be secured. It will be understood that other arrangements of the nozzles than the arcuate 15 arrangement shown may be provided so long as precautions are taken to secure a proper distribution of the compound across the surface to be treated, but the arrangement described is a particularly simple and effective one for securing 20 uniform distribution due to the spacing and uniform lengths of the pipes with consequent identical frictional resistance to the flow to each nozzle.

Shield means are preferably provided adjacent to the nozzles so as to protect the jets issuing from 25 the nozzles from the wind, and prevent waste of the material and imperfect distribution due to deflection of the jets by air currents. As illustrated, a curved sheet metal shield 79 is mounted on the frame outside of the jets by means of 30 brackets 71. The shield is illustrated as flaring outwardly so as not to interfere with the proper spread of the jets.

Cut-off valves are preferably provided in one or more of the outer pairs of pipes as indicated 35 at 75 in Figure 1. In this way the nozzles at the sides of the machine may be cut off when the machine is being utilized to coat a narrow strip of concrete.

For coating the vertical sides of a strip of concrete, the outer nozzles of the distributor are 40 preferably mounted on adjustable pipe brackets, as shown in Figure 7. As illustrated, the outer Y's are provided with downwardly extending parts 80 which have elbows 81 rotatably mounted on 45 their lower ends. Rotatably connected with elbows 81 are elbows 82 which carry pipes 83. Rotatably mounted on the pipes 83 are elbows 84 to which are swivelly connected elbows 85 carrying 50 pipe sections 86 on the ends of which are mounted the nozzles 22. Any well known form of swivel joint between the different pipe sections may be employed which will permit of adjustability of the sections and their retention in position after 55 adjustment. For instance, a joint having sufficient friction to hold its adjustment may be used, or any suitable form of releasable clamping means may be employed. With this arrangement it will be seen that the outer nozzles 22 may be directed on an angle as shown in full lines 60 in Figure 7, so as to spray downwardly and laterally upon the corners and vertical sides of the concrete; or the nozzles may be adjusted as shown in dotted lines, so as to spray directly against the vertical sides of the concrete.

Any suitable form of spray nozzle may be 65 employed in carrying out the present invention, such for instance as the improved construction of nozzle shown in Figures 5 and 6 which is particularly adapted for the purposes under consideration. This nozzle comprises a shell having a bell shaped cavity 100 therein, mounted in the lower end of which is an inverted cup-shaped 70 perforated plate 101 constituting a distributor and a strainer for the mixture of liquid and compressed air. This form of strainer does not

easily become clogged and it effectively distributes the liquid and air properly across the orifice of the nozzle. Mounted below the strainer 101 and held in place by means of a flanged ring 102 is a material diffusing plate 103 which has a 5 downwardly dished portion 104 in which is an elongated discharge orifice 105 preferably of a flattened oval shape as shown in Figure 6, which is narrower at the ends than at the center. This 10 type of diffusing plate forms a flattened and elongated jet or spray and the diffusing plates in all of the different nozzles are preferably so arranged that the longer axes of the orifices 105 are transverse to the line of travel of the distributing machine. The maximum coverage is 15 thus obtained from each nozzle. The proper form of the jet is also promoted by forming the orifice 105 in the curved or dish-shaped part of the diffusing plate. It will be understood, however that any other suitable form of nozzle may 20 be substituted for that shown.

For supporting the frame of the distributing machine carrying the nozzles so that the machine may be traversed over the surface of the concrete, a carriage may be provided which travels 25 upon the surface of the concrete itself, or a carriage may be provided which is supported independently of the concrete surface, for instance by means of wheels adapted to travel on the forms between which the concrete is laid. In 30 Figures 1, 2 and 8, a carriage of the former type is shown having a frame 110 which carries longitudinal supporting beams 111 upon which the beams 28 of the distributing frame are adapted to be removably secured in any suitable manner, 35 as by means of the bolts 112. The frame 110 carries wheels 113, preferably rubber tired, which are adapted to run on the surface of the concrete, one pair of such wheels being desirably 40 arranged for steering, a tongue 114 being provided for this purpose, and for conveniently moving the distributor along. The distributor frame and carriage are preferably made as light as possible so that the distributor may be moved over the surface of green concrete without injuring 45 the latter. This enables the distributor to be utilized to apply the coating to the concrete a short time after the latter is laid. The use of the device upon newly laid concrete is facilitated by mounting the air compressor and the main 50 liquid reservoir independently of the distributor and connecting them to the distributor by means of flexible pipes. In this way the weight of these parts is kept off the concrete.

In some cases it is advantageous to support the 55 distributor independently of the surface of the concrete, particularly in instances where it is desired to apply the coating to the concrete immediately after it has been laid, and before it has begun to set. In such instances a carriage is 60 employed which is constructed to span the strip of newly laid concrete and be supported by wheels travelling at opposite sides of the newly laid concrete surface. For instance, a carriage such as shown in Figures 9 and 10 may be employed 65 which comprises a frame 120 carrying longitudinal beams 121 to which the longitudinal beams on the frame are adapted to be bolted. The frame 120 is mounted on brackets 124 carrying an axle 125 on which are adjustably secured 70 flanged wheels 122 adapted to travel on the forms 123 between which the concrete is laid. The brackets 124 are adjustably secured to the frame 120 by suitable means such as bolts 126 so that the brackets with the wheels 122 may be moved 75

nearer together or farther apart depending upon the width of the strip of concrete to be treated.

While I have illustrated certain preferred forms of apparatus embodying the novel features of construction of my invention and by which my improved method may be practiced, it will be understood that modifications may be made in the apparatus and that my improved method may be performed in other ways than by 10 the apparatus shown. I therefore intend by the appended claims to cover my invention broadly in whatever way its principles may be utilized.

I claim:

1. A distributor of the character described 15 having small central chambers thereon for holding coating liquid and air under pressure, respectively, at least four spaced nozzles carried by said distributor, radial ducts connecting said nozzles with the liquid supply chamber, all of said 20 ducts being of equal length and size, and radial ducts connecting said nozzles with said compressed air chamber, all of said ducts being of equal length and size, whereby equal quantities 25 of liquid and compressed air will be supplied to each nozzle, said nozzles being spaced apart with the distances between the intermediate nozzles less than the distance between the outer and intermediate nozzles in such manner that the parallel paths traversed by the nozzles are approximately 30 equally spaced across the surface traversed by the distributor.

2. In a distributor of the character described, a frame, a pressure distributing receptacle of small diameter thereon, a multiplicity of individual distributing nozzles mounted on said frame 35 in the arc of a circle, said nozzles being spaced apart at progressively smaller intervals from the outside towards the center in such manner that the parallel paths traversed by the nozzle discharge orifices are approximately equally spaced 40 across the path traversed by the distributor, said pressure distributing receptacle being located at the center of said circle, and radial ducts of equal length and size connecting each of the nozzles with said pressure distributing receptacle.

3. In a distributor of the character described, a frame mounted on wheels, a plurality of depending nozzles arranged in arc shape transversely of said frame and adapted to project sprays upon 50 a concrete surface or the like over which the frame is traversed, and a downwardly depending and outwardly flaring arcuate shield carried by said frame outside of said series of nozzles to

protect the sprays delivered thereby from the wind, and means for supplying liquid and compressed air to each of said nozzles, said means comprising a pressure supply tank located at the center of curvature of the arc in which said nozzles are arranged, and radial ducts connecting said tank with the respective nozzles. 5

4. In a distributor of the character described, a frame, supporting wheels therefor, a series of downwardly depending spray nozzles carried by said frame and arranged in an arc extending transversely of the path of travel of the distributor, a pressure distributing tank located at the center of curvature of said arc, said tank being divided into upper and lower chambers by a transverse partition, radial ducts connecting each of said chambers with each of said nozzles, means for supplying the coating liquid under pressure to one of said chambers, and means for supplying air under pressure to the other of said chambers. 15

5. In a distributor of the character described, a frame, supporting wheels therefor, a series of downwardly directed spray nozzles carried by said frame and arranged in an arc extending transversely of the path of travel of the distributor, a pressure distributing tank located at the center of curvature of said arc and radial ducts of equal size and length connecting said tank with the respective nozzles, said nozzles being spaced apart 30 at progressively smaller intervals from the outside towards the center in such manner that the parallel paths traversed by each nozzle are approximately equally spaced across the surface traversed by the distributor. 35

6. In a distributor of the character described, a frame, supporting wheels therefor, a series of downwardly directed spray nozzles carried by said frame and arranged in an arc extending transversely of the path of travel of the distributor, a pressure distributing tank located at the center of curvature of said arc and radial ducts connecting said tank with the respective nozzles, said nozzles being spaced apart in such manner that the parallel paths traversed by each 40 nozzle are approximately equally spaced across the surface traversed by the distributor, and a downwardly depending shield of arc shape carried by said frame and extending around outside of said nozzles for protecting the sprays delivered thereby from the wind. 45

ALBERT D. SAUNDERS.
